COMBINATION KITCHEN CABINET AND BREAKFAST TABLE

Oren B. Marshall, Kansas City, Mo.

Application April 10, 1950, Serial No. 9,101

Term of patent 14 years

(Cl. D33—19)

To all whom it may concern:

Be it known that I, Oren B. Marshall, a citizen of the United States, residing in Kansas City, in the county of Jackson, and State of Missouri, have invented a new, original, and ornamental Design for a Combination Kitchen Cabinet and Breakfast Table, of which the following is a specification, reference being had to the accompanying drawing, forming a part thereof, wherein:

Fig. 1 is a perspective view of a combination kitchen cabinet and breakfast table, showing the same as used for a kitchen cabinet; and

Fig. 2 is a perspective view showing the same as used for a breakfast table.

The side and end not illustrated are identical with the side and end respectively, shown in Figs. 1 and 2.

I claim:

The ornamental design for a combination kitchen cabinet and breakfast table, as shown and described.

OREN B. MARSHALL.
